DISHWASHING MACHINE AND METHOD

Robert H. Hunter, Gates Mills, and Elmer J. Kasper, Cleveland, Ohio; said Kasper assignor to said Hunter

Application October 2, 1947, Serial No. 777,388

14 Claims. (Cl. 134—25)

1

This invention relates to washing machines or devices and more particularly to stream or jet washers for dishes and the like and to a method of washing dishes in the washing machine. The cleansing action of high velocity water jets has long been known and a number of dishwashers have been designed to operate on the high velocity jet principle. Washers of this character are customarily of complicated or intricate design, employing a large number of components which not only make the machine or washer expensive to build and relatively large and cumbersome, but also make its service and upkeep a costly factor. The present invention is thus directed to improvements in dishwashers, particularly of the jet type, special attention being given to the simplification of such washers to the end that they may be produced economically with a minimum number of parts and so that they will give long service without costly maintenance or service being required.

One of the principal objects is to provide a jet type washer, and method of washing dishes therein, in which the energy in the ordinary city water system is utilized to move the dishes being washed relatively across the path of the jets. More specifically, the invention aims to provide a dishwasher in which dishes supported in a rotatable basket are subjected to the action of a plurality of fixed jet such that the energy of the jets causes rotation of the basket and the resulting basket movement causes the dishes to be moved or shifted so that the jet sweep over the dish surfaces, cleansing the latter. As a related object and advantage the dish basket is made to rotate in and with a body of washing water containing a detergent so that the whirling and swirling of the water causes the latter to flow over and around the dishes and other objects immersed therein to effect a thorough and rapid cleansing of the latter.

Other objects and advantages of the invention are concerned with such features as the utilization in a single jet nozzle of a plurality of jet orifices of different sizes, some of the jet orifices being directed tangentially with respect to dishes in the basket to rotate the basket in the tub as well as to cleanse the dishes and others of the jets being arranged radially, or substantially so, primarily to cleanse the dishes and turbulent or churn the water in the tub; and the provision of a top mounted nozzle in combination with a transparent section in the top through which the action of the jets from the nozzle can be observed to determine the character of the washing action.

55

2

and when the washing action has been completed.

The above and other objects of the invention will become apparent from the following detailed description of a preferred embodiment of the invention, this description being made by reference to the accompanying drawings forming a part of this specification and in which like parts throughout the several views are indicated by the same letters and numerals of reference.

10 In the drawings:

Figure 1 is a vertical sectional view through the assembled dishwasher, parts being broken away and removed;

15 Fig. 2 is a top plan view of the washer, partly in section and with parts broken away and removed, this view being taken substantially along the line indicated at 2—2 of Fig. 1;

20 Fig. 3 is a fragmentary top plan view of the washer, partly in section and with parts broken away, this view being slightly enlarged with respect to the preceding figure;

25 Fig. 4 is a fragmentary transverse view through the washer, partly in section and with parts broken away, this view being taken substantially on the line indicated at 4—4 of Fig. 3;

Fig. 5 is a sectional detail taken substantially on the line 5—5 of Fig. 2, showing the nozzle structure;

30 Fig. 6 is a sectional detail taken substantially on the line 6—6 of Fig. 5;

Fig. 7 is a fragmentary elevational detail taken substantially on the line 7—7 of Fig. 1 and enlarged with respect to that figure;

35 Fig. 8 is a sectional detail to show the drain and valve structure, taken substantially on the line 8—8 of Fig. 7;

Fig. 9 is a sectional detail similar to Fig. 8 showing the closure for the discharge opening in open position;

40 Fig. 10 is a sectional detail taken substantially on the line indicated at 10—10 of Fig. 8 and enlarged with respect to that view, parts being broken away and removed; and

45 Fig. 11 is a sectional detail taken substantially on the line indicated at 11—11 of Fig. 8 and enlarged with respect to that view, parts being broken away and removed.

The present washer, of the portable type, is particularly suited for domestic use where space is at a premium. The device can be stored in a cupboard or closet and set up on a sink drain board for use in washing the family dishes after every meal. Under such circumstances the weight of the appliance is an important factor and special attention has been given to making

a washer which is light in weight so as to be readily moved about by a housewife without objectionable inconvenience.

The washer comprises an upright open topped tub A which may be circular in shape, as shown, or if desired, square or other polygonal shape. The tub has a removable top or closure B. Inside the tub is disposed a dish and cutlery receiving assembly C which is mounted for rotation preferably about a vertical axis. Cleansing liquid is introduced through a nozzle means or assembly D into the interior of the tub in the form of a suitable jet or jets to impinge on dishes and cutlery in the receivable or assembly C. The high velocity jets from the nozzle impinge on dishes and other articles to be washed that are supported in the receivable C causing the latter to rotate within the tub. Thus the jets of cleansing liquid are made to sweep over the surfaces of the articles to be washed at various angles, providing efficient washing action.

A drain and closure or valve means is provided for retaining in the tub A the washing liquid that is introduced through the nozzle D. The liquid level progressively rises in the tub during the washing process and a cleansing agent such as soap or other detergent is initially introduced into the tub so that the swirling of the liquid over the immersed dishes and cutlery has an effective cleansing action thereon. The outlet valve or closure means is also arranged for draining the tub rapidly so that when the cleansing operation is completed the liquid can be quickly released from the tub and rinsing liquid can be introduced through the nozzle D.

Tub structure

The tub A is preferably formed of sheet metal by a spinning or drawing process, the metal base being either stainless steel, aluminum for lightness, or other suitable material treated to resist corrosion. The tub has a circular flat bottom 1 the edges of which are integrally joined by upwardly curved marginal portions 2 to upstanding cylindrical side walls 3. Around the upper edges of the side walls 3 is formed an outwardly offset upstanding flange portion having its edge bent or rolled outwardly to provide a circular bead 4. At the base of the offset flange a radial shoulder 5 extends circumferentially around the entire upper edge of the tub below the rolled edge 4 to provide a seat for the cover.

The top or cover B includes a sheet metal ring 6 which may be stamped or spun to the desired circular shape. The outer margin of the ring has an integral depending flange 7 which is circumferential in extent and terminates in a rolled bead 8 that rests on the shoulder 5 of the tub, the cover bead being received within the bead 4 on the upper edge of the tub.

The circular inner edge of the metal ring 6 is rolled or bent to form an S-shaped flange 9 which provides a circumferential channel. The channel opens inwardly and embraces edge 10 of a circular transparent member or disc 11. The disc 11 of molded glass or plastic is centrally formed with an integral upstanding grip or handle 12 by means of which the lid or closure B can be manipulated in removing it from and placing it on the tub A. The bead 8 of the closure B has a light friction fit within the flange offset of the tub so as to retain the cover in the position in which it is placed in the tub against the reactive forces resulting from the jets of the nozzle D.

An upright central post or spindle 14 of brass or plated steel is secured at its lower end, as by a press fit, in upstanding cylindrical supporting sleeve 15 formed at one end with an integral circular attaching flange 16 riveted at 17 to the tub bottom 1 in the center of the latter. The flanged sleeve 15 is preferably of brass or other wear resisting metal and its upper end is received within the socket of the basket to guide the latter and to serve as a bearing, as will later appear.

Basket structure

The article receiving receptacle or assembly C includes a dish supporting basket formed of open mesh or perforated metal. The basket conforms in general to the shape of the tub A and has a flat circular bottom 19, the circular margin of which is connected by upwardly curved portions 20 to upstanding, substantially cylindrical side walls 21. The basket is thus entirely open across its top to receive dishes and other articles to be washed.

A tubular metal socket member or sleeve 23 is received over the spindle 14 to support the article receiving receptacle C thereon. The sleeve is formed at its lower end with a radial flange 24 on which rests a circular washer or ring 25. The central aperture in the washer receives the body of the socket member 23 and the disc underlies the bottom 19 of the basket to support the latter. A flanged collar 26 is forced or press fitted over the socket member 23 and against the portions of the basket bottom 19 that surround the socket member so as to hold the basket bottom against the supporting disc 25, thus retaining the parts in assembled relation. The basket may be galvanized or treated to make it corrosion resistant by dipping in molten tin before assembly.

Top or closed end 28 of the socket member 23 bears on the upper end of the spindle 14 to support the basket and article receiving assembly C above the bottom 1 of the tub, space 29 thus provided below the basket serving to receive any solid particles that may be washed off the dishes during the cleansing process. A clearance 30 between the basket side walls 21 and the tub side walls 3 is also provided so that the basket may be freely rotated on the spindle 14 without the basket rubbing on the side walls of the tub.

The socket end 28 may bear directly on the top of the spindle 14 or, preferably, an anti-friction device such as a steel ball 32 is inserted between the parts, this ball being retained in place and centered on the spindle 14 by a brass bearing thimble or cap 33 which is retained on the upper end of the spindle as by a press fit. The steel ball 32 projects through a central opening in the end of the cap 33. The opening in the cap is of smaller diameter than the ball 32 so that the latter is caged within the cap. A hardened plug 34 threaded through the end 28 of the socket member 23 and coaxial to the latter contacts and bears endwise against the steel ball 32. This plug may be shifted axially in the sleeve end to raise or lower the basket in the tub and thereby adjust the clearance or space 29 between the basket bottom and the bottom of the tub. The basket sleeve or socket 23 has a running fit about the bearing cap 33 and the sleeve 15 which serves as bushings or guides to prevent wobbling of the socket on the spindle.

Article spacer and cutlery cage

In the center of the basket and forming a part 75 of the article receiving receptacle assembly C is

a cutlery cage formed of metal rods or heavy gauge wire welded or soldered together. The cage comprises a pair of bottom radial elements or bars each of which is formed to provide arms 35 and a semi-circular guide portion 36. The guide portions 36 of the two elements are arranged cooperatively to form a circular collar which slidingly embraces the tubular socket member 23 and the collar 26 of the latter so that the cage can be readily lifted as a unit off the guide sleeve. Circular rings 37 and 38 are welded or soldered to the radial arms 35 in concentric relation about the center or socket sleeve 23. At equidistantly spaced intervals about the outer ring 38, the latter is formed with a number of reversely bent upstanding loops or convolutions 39 which may be integral with the ring, or as shown, made of separate pieces welded in place. A ring 40 of the same diameter as the ring 37 is supported above the latter by vertical elements 41 which are welded to the two rings. The upstanding loops 39 serve as stops against which may be disposed the bottoms of plates E that are stacked in the basket in upright fashion. The plates are arranged fanwise on their edges about the center of the basket much in the fashion of the blades of water and steam turbines. The ring 40 supported above the level of the basket bottom 19 and radially inwardly from the stops 39, serves as a fence or rail to prevent stacked dishes from sliding inwardly into the central part of the basket during the washing action. Some of the stop loops 39 are formed with depending portions 42 which extend downwardly through the interstices of the basket bottom 19 so as to interlock the basket and cutlery cage for rotation in unison.

In the center of the cage structure a relatively tall retainer for cutlery is formed by a helical or spiral wire coil 43. This coil is preferably tapered to spread cutlery for better cleansing; the small diameter end being at the bottom and the lowermost turn being secured as by welding or soldering to the radial arms 35 of the cage structure. A number of upright stiffeners 44 are disposed at intervals about the helical coil 43 and are welded or soldered to the turns of the latter.

Although the cage structure is normally disposed in the center of the basket, being located by the interfitting relation of the sleeve 23 within the semi-circular locating portions 36 of the bottom cage elements and is interlocked with the cage bottom by the depending portions 32 of the stop loops 39, the cage may be removed as a unit by withdrawing it upwardly from the basket off the tubular socket member 23. When the cutlery receptacle or cage is thus removed the basket is cleared for receiving relatively large dishes or pans to be washed in the device.

Washing liquid or water is supplied to the nozzle means D through a flexible conduit such as a tubular hose 45 having an end connector 46 that is screwed onto or held by a spring pressed clutch collar on a mating fitting secured on a tube 47 which is pressed into an opening in body portion 48 of the nozzle. The other end, not shown, of the flexible conduit 45 is provided with a conventional fitting for attachment to a sink hot water or mixing faucet so that the device can be thus connected to the relatively high pressure water system of the house.

The nozzle body 48 is secured to the outside of the cover ring 6 as by screws 50 and is formed with an internal chamber 51 in communication

with the passage in the inlet tube 47. A jet head or button 52 is secured in a recess in the underside of the nozzle body as by a press fit, or by being threaded into the same. This jet head is in the form of a hollow cup or thimble and has an outer closed end portion 53 which projects through an opening in the cover ring 6. A number of jet orifices or passages 54, 55, 56 and 57 are formed in the button or cup 52 in communication with internal chamber 58 of the cup which is open to the chamber 51 in the nozzle body and receives high pressure liquid or water from the flexible conduit 45.

All of the jet orifices open into the space beneath the lid or closure B of the washer and are arranged to direct high velocity divergent jets of the washing water into the interior of the tub A. The jets are so arranged as to form a coned pattern, the jets being directed in different directions from one another. For example, jet 54a from the jet orifice 54 and jet orifice 55a from the orifice 55 are directed somewhat tangentially with respect to the basket or receptacle C so as to drive and impinge against the basket and articles in the latter and to thereby cause rotation of the receptacle and contents as a unit.

Jet 56a from orifice 56 is substantially radially directed with respect to the axis of rotation of the basket and has substantially no effect on the rotation of the basket, but has a sweeping action over the surface of articles in the basket to dislodge particles being cleansed from the articles. This jet or water stream 56a from the orifice 56 drives into the central portion of the tub so as to churn the central portion of the body of water which collects or accumulates in the tub during the washing operation. This action is particularly beneficial for the reason that the jet 56a tends to break up any suds pad or other accumulation in the center of the tub and to cause the suds and washing powder to become distributed more evenly and uniformly throughout the mass or body of water which is swirling around in the tub due to the action of the jets. The radial jet 56a driving into the center of the tub also impinges directly onto cutlery and other small items supported in the helical cage 43 so that such cutlery is embroiled in a churning mass of swirling suds water which effectively cleanses such articles.

Jet 57a from the orifice 57 is directed counter or opposite to the jets 54a and 55a and generally tangentially to the rotation of the basket so as to tend to oppose the rotation of the latter. The reverse action jet 57a thus acts to retard or slow the rotation of the basket. The retarding jet also drives into the body of water in the tub creating a churning turbulence in the water and reducing the tendency of the rotating mass or body of water to form a central vortex or whirlpool. A wave crest in the suds water is also created by the back jet 57a and washes over the oncoming dishes and plates carried around by the basket.

In the present washer a relatively large flow or movement of the suds or detergent-containing water is created over the surfaces of the dishes and plates being washed by retarding the rotational movement of the basket or receptacle C so that it moves at a relatively slow speed such as from about 10 to about 30 revolutions per minute, preferably in the neighborhood of about 20 revolutions per minute. The driving jets 54a and 55a accelerate the water between adjacent plates 70 in the region of jet impingement causing the

water which is laden with suds or washing powder to scrub over the adjacent dish surfaces in a strong scouring action.

A modulating effect on the rotational speed of the basket or the receptacle is obtained by the effect of the retarding jet 57a. This jet, which is directed to impinge on the oncoming articles carried around into its path by the basket rotation, has a relatively greater retarding effect as the rotational speed of the basket is increased. On the other hand, the driving jets 54a and 55a which are directed in the same general direction as the movement of the rotating dishes become less effective or impinge with less force on the dishes and plates as the rotational speed of the basket increases. Thus the forces of the driving jets and the force of the retarding jet tend to become balanced as the rotational speed of the basket increases to equilibrium. The sizes of the jets are so proportioned that without using an excessive quantity of water in a washing cycle the basket can be made positively to rotate at what may be termed a substantially minimum speed merely sufficient to move the plates and dishes sequentially around into the paths of the jets.

During the intervals when the dishes are not directly subjected to the action or impingement of the jets, but are moving around in the tub, they are, of course, undergoing a soaking and gentle flushing action in the turbulent suds-containing water. Hence, the washing cycle includes alternate periods of soaking or flushing with detergent containing water and periods of vigorous scrubbing and scouring action in which the detergent containing water is driven over and across the surfaces of the articles by the energizing action of the jets.

The effect or result of a multiplicity of divergent water streams which are directed into the water mass in the tub at different angles is to create a stronger turbulent flow which causes the water to scrub over the surface of the dishes or other articles being cleansed in a vigorous back and forth washing action.

The apertures or openings in the nozzle button or jet head 52 must be sufficiently long to provide an adequate guiding or forming action on the water being forced therethrough so as to avoid objectionable spreading out of the water streams or jets after leaving the nozzle. In the washer of the present invention the washing action is obtained in a large measure through the swirling and scrubbing of the water mass in the tub over the surfaces of the dishes as well as by the direct scrubbing or scouring action of the jets impinging and driving against the dishes. Therefore, it is important to provide relatively fine, sharp jets which create a churning and turbulent action in the water mass without excessively augmenting or adding to the quantity of water which would result in filling the tub at too fast a rate. On the other hand, the jet passages must not be excessively long or the frictional resistance to the flow of the water therethrough results in low velocity jets which do not have the desired churning action in the water and which do not provide the desired energy to rotate the basket.

In forming the jet passages, each of which is preferably round in cross section, extreme care is exercised to avoid burrs and irregularities in finish. The jet apertures or passages may be formed by drilling in a jig, followed by reaming which removes burrs and provides smooth inter-

nal walls along the length and at the orifices of the jet passages.

Of particular advantage in the present washer is the use of relatively large jet passages for the orifices 54 and 55, which produce the basket rotating or driving jets, in combination with the relatively small jet passages for the orifices 56 and 57, which produce the churning or suds dispersing jet and the retarding or speed modulating jet respectively.

The precise sizes of the passages in the nozzle button 52 are not critical, but are made sufficiently large to form jets that will have the requisite energy to turn the basket or receptacle C and yet 15 sufficiently small to restrict the flow of water within reasonable limits so that the hot water used in a single washing cycle is within the capacity of the ordinary home hot water heating system. It is desirable to restrict the flow so 20 that a complete washing and rinsing cycle consumes approximately 10 gallons or less of hot water.

The jet head or nozzle button 52 has an end wall 53 that is relatively thick to provide substantial length in the jet passages. For example, a satisfactory end wall is one which is about $\frac{1}{16}$ " thick to about $\frac{3}{16}$ " thick. A wall of such thickness, although it may be thicker or thinner, forms 25 passages of adequate length to properly guide and direct the jets in the desired directions without spreading or fanning out of the jets. Thus the energy of each of the jets is concentrated substantially at the point of impingement.

While the diameters of the jet passages can be 30 varied to suit local conditions the desired volumetric water flow is obtained in the washer when used in an average home supplied by a modern, large city water system, and when, by way of example, the jet passages 54 and 55 are each 35 reamed to a diameter of about .0915 inch to about .1115 inch, preferably about .1015 inch and when the passages 56 and 57 are each reamed to a diameter of about .071 inch to about .091 inch, preferably about .081 inch.

As previously mentioned the flexible conduit or 40 hose 45, which supplies hot water under high pressure to the nozzle head, is connected to a sink hot water or mixing faucet. In turning on the faucet at the beginning of the washing cycle the flow is adjusted at the faucet to give the pressure 45 which will result in strong impingement of the driving jets against the dishes and articles in the basket but which will not use an excessive quantity of hot water during the cycle. In this manner the water flow is manually regulated or modulated at the faucet by the person using the dishwasher to give the desired washing action.

Overflow and drain

In the side wall of the tub adjacent the top is 60 an overflow or outlet opening 60 which releases the liquid from the tub chamber at a predetermined height so as to prevent overflowing of the tub. In the tub bottom is a discharge or drain opening 61, normally covered by a closure to be 65 later described, releases the washing liquid or water from the tub when the washing action has been completed.

A common drain structure is provided to receive and carry off liquid discharged from the tub through both the overflow opening 60 and the drain opening 61. This structure or unit comprises a chambered drain member 62 formed as by casting of light metal such as aluminum. It is 75 a hollow shell-like structure received over a por-

tion of the curved corner wall 2 of the tub so as to define a drain chamber 63. A deformable sealing gasket 64 of cork or rubber is interposed between the various edge portions of the drain member 62 and the walls of the tub A to provide a water-tight joint therebetween. A number of screws such as indicated at 65 are threaded into the drain member through the tub walls to secure the parts together. So that the drain member will underlie a portion of the tub bottom as well as extend up over a portion of the side wall 3, it is made in somewhat of an L shape. The internal chamber 63 is also somewhat L shaped and both the drain member and the chamber therein overlie and partially embrace a corner portion of the tub at the angle of the bottom and side walls of the latter.

Extending upwardly from the top portion of the drain casting 62 and as a continuation thereof is a channel member or plate 67 which overlies a portion of the tub side wall 3. A longitudinally extending central portion of the channel plate is bowed outwardly and is spaced from the tub wall while edge portions 68 of the plate make continuous contact with the tub wall to provide an overflow drain passage or passageway 69 which extends down the outside of the tub and connects to the drain chamber 63 of the drain member 62. The channel plate 67 is disposed across the overflow opening 60 so that the latter is continuous with the drain passage 69 and the upper end of the plate is formed inwardly at 70 to make contact with the tub wall above the overflow 60. The lower end of the plate 67 extends within a recess provided therefor in the upper end of the drain casting 62 and is secured in place as by a screw 71 so that the overflow passage 69 is continuous with the drain chamber 63. A deformable gasket 72 of rubber or cork is interposed between the edges of the channel plate 67, tub walls and the drain member 62 so as to provide fluid-tight seals. In the outer angle of the drain member 62 the wall of the latter is formed with an aperture or orifice 73 which serves as an outlet through which liquid received in the drain member is discharged into the bowl of the sink on which the washer is mounted.

To support the washer off the drainboard of the sink a foot 74, formed with a threaded stem 75, is screwed into a threaded opening in the inner end of the drain member 62. Other feet 76 are secured to the tub bottom at points spaced from the foot 74 to support the tub in horizontal or level position. Desirably, rubber cushions 77 are fitted into and retained in recesses in the bottoms of the tub feet 74 and 76 to prevent sliding of the tub on a supporting surface and to prevent marring of a porcelain or enamel surface by the tub feet. When the washer is used on an inclined drainboard the tub can be levelled by screwing the threaded stem 75 into or out of the drain casting 62 so as to compensate for the slope of the drainboard. It is therefore desirable to employ only two of the supporting feet 76 in addition to the adjustable height foot 74.

A closure or quick acting valve for the drain opening 61 is supported in and wholly carried by the member 62 of the drain assembly. The valve comprises a closure member 80 which may be made to underlie the opening 61 and carries a deformable sealing pad or gasket 81 engageable with the bottom wall 1 of the tub about the opening 61 to seal the latter and prevent the flow of water out of the tub. The closure 80 is a metal stamping formed at one end with an upstanding arm

portion 82, the upper end of the arm having a reverse bend 83 hooked through a slot 79 in a supporting bracket 84. The closure piece or member is thus of L shape and has rolled or flanged edges 85 which strengthen the stamping to prevent distortion or bending in operation. The bracket 84 is hat shaped, having like end portions that are secured to the inside of the upstanding wall of the drain member 62 by rivets 86. The edges of the reversely bent portion 83 on the upper end of the closure member arm are confined between side portions of the bracket 84 so as to prevent lateral shifting of the closure while permitting the latter to swing or pivot in an arc between the broken and full line positions indicated in Fig. 9.

Drain valve mechanism

The closure valve normally drops by gravity 20 to the open position shown by the full lines in Fig. 9 in which the drain opening 61 in the bottom of the tub is clear or substantially unobstructed for the discharge of water or washing liquid into the drain chamber 63. For moving 25 the closure 80 to swing upwardly across the drain opening 61 into the sealing position shown in full lines in Fig. 8 and in broken lines in Fig. 9 a mechanism is provided which may be manually operated externally of the drain assembly so that 30 a housewife can open and close the drain without coming in contact with the wash water which besides being dirty or gritty, may be at an elevated temperature and may contain strong or irritating cleansing agents.

The drain opening and closing mechanism comprises a stub shaft 87 journaled in a bushing supported in the upright wall portion of the drain member 62 just below the bracket 84. The outer end of the stub shaft 87 is formed with a reduced 35 diameter portion 88 which receives a hand lever 89 of cast metal or molded plastic composition, the lever being secured on the shaft as by a set screw 90. The squared inner end of the shaft 87 is received in a square opening in a cam lever 40 21, the end of the shaft being riveted or peened over the lever to secure the latter on the shaft. On the end of the lever 91 an angularly disposed cam portion 92 is formed with inclined edges one 45 of which, upon rotation of the shaft 87 by the hand lever 89 through about ninety degrees, is moved into engagement with the lower part of the upright portion 82 of the closure so as to swing the closure upwardly from the open or full line position shown in Fig. 9 to the closed position 50 shown by the broken lines of that figure and by the full lines in Figs. 1 and 8. Reverse movement of the hand lever withdraws the cam from the upright portion 82 of the closure, allowing the latter to drop by gravity and the pressure of the 55 water to quickly open the drain. The valve operating mechanism is quick operating and thus functions to effect complete opening or closing of the valve in a one-quarter turn of the operating lever 89. Reference is made to copending application for patent Serial Number 336,982, filed 60 February 16, 1953, describing and claiming certain of the features referred to above.

Operation

In utilizing the washer of the present invention to cleanse articles such as plates and dishes E of a table service and table cutlery, the articles, after a preliminary rinsing or scraping to remove loose food particles and the like, are placed in the receptacle C in the manner previ-

ously described, there preferably being no water in the tub. The dishes are thus angled out from the center of the basket in upright turbine-like arrangement with the concave sides of the dishes all facing around in the same direction so as to receive the direct force of the large driving jets 54a and 55a. A quantity of suitable washing powder of the detergent type is introduced into the tub, preferably in the center thereof, the lid or cover B is placed on the top of the tub, and high pressure water, preferably at an elevated temperature such as from about 120° F. to about 160° F. is supplied to the nozzle D through the conduit 45.

The high velocity jets of water directed into the tub through the passages 54, 55, 56 and 57 drive against the plates and dishes and also the cutlery, scrubbing food and other foreign particles off the surfaces thereof. This scrubbing action is very strong at the beginning of the washing cycle, there being little or no water in the tub, and the jets impinge directly onto the surfaces of the dishes and plates. By reason of the greater energy of the heavier streams or jets from the relatively large passages 54 and 55, a turning force or couple is exerted on the articles in the basket and on the basket itself causing the latter to turn about the supporting post 14. This turning of the basket starts very quickly because there is no large body of water in the washer to retard the motion and additionally because of the anti-friction means embodied in the rotatable support for the basket.

As the several jets continue to drive into the basket area, the jets 54 and 55 turning the basket while the jets 56 and 57 churn the water and break up the agglomeration of suds or washing powder that tends to form, the water level progressively rises in the tub.

The turning of the basket brings the spaces between the dishes sequentially into the paths of the driving jets 54 and 55. These jets act on the detergent or suds-containing water in such spaces, driving the water through the channels between dishes so that the water scrubs over and scours the surfaces of the articles in an effective cleansing action. The whipping and churning of the suds-water, forcing the same to flow rapidly across the dish surfaces, is effected in a turbulent washing zone in the tub by the driving jets and also by the retarding and center jets.

Upon reaching the level of the overflow opening 60 the suds-water flows out the latter and is discharged into the sink through the drain orifice 13. The washing powder or detergent contained in the water has the effect of causing the grease, soil and dirt removed from the dishes to rise to the top of the water bath to be entrained in the outflowing water and discharged through the overflow opening. Heavy particles of dirt and soil removed from the dishes and which do not migrate upwardly tend to settle into the bottom of the tub below the level of the rotating basket.

After the water starts to run out of the overflow opening the operation of the washer is continued by maintaining the supply of water to the jets for a short period of time such as a minute or so. The drain closure 80 is then released to drop away from the discharge opening 61 allowing the wash water to drain from the tub. As the water flows out of the tub the jets are continued in operation so that the dishes are thoroughly rinsed with fresh hot water supplied through the nozzle D. The rinsing action, which takes place continuously as the level of the wash

water recedes, leaves the articles and also the interior of the tub and the basket in a clean, fresh condition such that no special washing or wiping is required.

When the last of the wash water has been emptied from the tub through the discharge opening 61 and clear rinse water appears to be flowing out the discharge 73 the supply of water to the nozzle D is shut off. The cover B is then removed from the washer, allowing the free circulation of ambient drying air over the articles in the washer. Since it is unnecessary for persons operating washers of this type to place their hands in the wash water or rinse water, the water used may be very hot, if desired, and the ensuing drying action is therefore relatively rapid. Accordingly a short time after the removal of the cover from the washer after the washing cycle, the articles are customarily dry enough to permit them to be removed from the washer and re-used or placed in the cupboard without special wiping.

Although the principles of the present invention can be utilized to advantage in a washer employing more than a single nozzle, the use of more than one nozzle has a proportional effect on the quantity of hot water required for each washing cycle. In relatively small washers for domestic use, it is desirable to keep the hot water requirement to a minimum and the single nozzle head washer of the type shown in the present drawings accomplishes this objective while yet obtaining an efficient and relatively rapid washing action.

By providing the transparent panel 11 in the cover B it is possible for the operator to observe the washing action and ascertain that an adequate quantity of washing powder or other detergent is present and to see that the articles have been properly or evenly distributed about the basket so that the jets are effective to rotate the basket in the manner described.

The jet principles utilized in this washer contemplate provision of a multiplicity of jets, a plurality of which act as driving jets to rotate the basket structure and at least one of which acts in opposition to the rotation to churn or turbulent the water and to avoid formation of a central vortex or whirlpool. The jet principles also contemplate the use of a jet which is radial or substantially so, which drives into the central portion of the rotating mass of water to break up suds pads and accumulations of washing powder and to scrub the cutlery in the central cage structure as well as to sweep radially over the dishes and plates as the latter move in succession across the path of such jet.

The principles of the present invention may be utilized in various ways, numerous modifications and alterations being contemplated, substitution of parts and changes in construction being resorted to as desired, it being understood that the embodiment shown in the drawings and described above and the particular method set forth are given merely for purposes of explanation and illustration without intending to limit the scope of the claims to the specific details disclosed.

What we claim is:

1. In a dishwasher having a tub, a basket and means supporting the same for rotation in the tub, a cover for the tub, a nozzle mounted eccentrically on the cover, and means for conducting high pressure liquid to the nozzle, the nozzle having a plurality of diverging orifices for directing a number of high velocity streams of

liquid into the tub, some of said streams being directed against the basket to rotate the latter and at least one of the streams opposing such rotation.

2. In the process of washing dishes and like articles in a rotary basket by water jet action the improvement which comprises in combination directing a plurality of separate fine streams of high velocity water downwardly from a locus wholly above the basket and the articles directly against articles in the basket while the latter is rotating, and progressively immersing the rotating basket and the articles contained therein in a liquid cleansing solution while the water streams are so directed.

3. In the process of washing dishes and like articles in a rotary basket by water jet action the improvement which comprises in combination directing a plurality of separate fine streams of high velocity water downwardly and divergently from substantially a common point of origin above the basket and the articles directly against articles in the basket while the latter is rotating, and progressively immersing the rotating basket and the articles contained therein in a liquid cleansing solution while the water streams are so directed.

4. The method of washing dishes and like articles which comprises supporting the articles in spaced relation for rotation as a group about an upright axis and directing a plurality of fine high velocity water streams downwardly and obliquely to the horizontal against the articles from substantially a common point of origin wholly above the articles, some of said streams being directed to impinge directly on the articles so that the energy of the last mentioned streams effects said rotation of the articles and at least one other of the streams being directed to impinge directly on the articles to oppose such rotation.

5. The method of washing dishes and like articles which comprises supporting the articles in spaced relation for rotation as a group about an upright axis and directing a plurality of fine high velocity water streams downwardly against the articles from substantially a common point of origin located wholly above the supported articles, some of said streams being directed to impinge directly on the articles so that the energy of the last mentioned streams effects said rotation of the articles and at least one other of the streams being directed to impinge directly on the articles to oppose such rotation.

6. In the process of washing dishes and like articles in which the articles are supported within a tub and rotated as a group about an upright axis and subjected to detergent and water jet action the improvement which comprises in combination directing a plurality of separate fine streams of high velocity water downwardly and obliquely to the horizontal from a locus wholly above the articles directly against the articles, and collecting the water from the streams in the tub so that the water level progressively rises in the tub to immerse the rotating articles while the latter are being impinged upon by the downwardly directed water streams.

7. In the process of washing dishes and like articles in which the articles are supported within a tub and rotated as a group about an upright axis, the improvement which comprises in combination forming a detergent solution in the bottom of the tub, directing water streams downwardly and obliquely to the horizontal from a

locus wholly above the articles directly against the articles, collecting the water from the streams and commingling it with the detergent solution to form a liquid bath and so that the surface of the liquid bath progressively rises in the tub to progressively immerse the rotating articles while the latter are being impinged upon by the downwardly directed water streams, and then draining the tub.

10 8. In the process of washing dishes and like articles in which the articles are supported within a tub and rotated as a group about an upright axis, the improvement which comprises in combination forming a detergent solution in the bottom of the tub, directing water streams downwardly and obliquely to the horizontal from a locus wholly above the articles directly against the articles, collecting the water from the streams and commingling it with the detergent solution to form a liquid bath and so that the surface of the liquid bath progressively rises in the tub to progressively immerse the rotating articles while the latter are being impinged upon by the downwardly directed water streams, removing the liquid bath from the tub, and continuing the directing of the water streams downwardly against the articles during the removal of the liquid bath to rinse the articles.

9. In combination in a washer of the type having a tub and an article receiving basket mounted in the tub for rotation about an upright axis, a cover for the tub, a chambered member carried by the cover and having a nozzle portion extending through the cover, and a flexible conduit and means for connecting the latter between said member and a source of water under pressure to supply high pressure water to the chambered member, the nozzle portion of the chambered member being formed with a plurality of jet passages communicating with the interior of the chambered member to receive high pressure water from the latter, and said jet passages being divergent and disposed to direct separate streams of water downwardly into the basket in divergent relation substantially from a common origin.

10. In combination in a washer of the type having a tub and an article receiving basket mounted in the tub for rotation about an upright axis, a cover for the tub, a chambered member supported on the outside of the cover, a flexible conduit and means for connecting the latter between said member and a source of water under pressure to supply high pressure water to the chambered member, a nozzle on the chambered member and projecting downwardly through the cover between the axis and walls of the basket, and a plurality of jet passages in the nozzle, said jet passages being divergent and disposed to direct separate streams of water downwardly into the basket in divergent relation substantially from a common origin.

11. In combination in a washer of the type having an open top tub and an article receiving basket mounted in the tub for rotation about an upright axis, a cover disposed across the top of the tub, a nozzle member carried by the cover and having a plurality of divergent jet passages arranged to direct separate water jets downwardly into the basket in divergent relation from substantially a common origin, means for supplying high pressure water to the jet passages, means providing an overflow drain in the tub permitting filling of the tub with water to a predetermined level below the tub top and to a

depth sufficient substantially to immerse completely the basket and articles contained therein, said drain providing a discharge exit for excess water introduced into the tub by the jets from the nozzle member while the water in the tub is at said level, and means operable optionally for draining water from the tub at a rate greater than introduced through the nozzle member to permit emptying of the tub of water while water is supplied continuously to the jet 10 passages in maintenance of the jets.

12. In combination in a washer of the type having an open top tub and an article receiving basket mounted in the tub for rotation about an upright axis, means for supplying water to 15 the tub in the form of a plurality of separate, relatively fine high velocity jets directed downwardly into the basket, means providing an overflow drain in the tub permitting filling of the tub with water to a predetermined level below the tub top and to a depth sufficient substantially to immerse completely the basket and articles contained therein, said drain providing a discharge exit for excess water introduced into the tub by the jets while the water in the tub 25 is at said level, and means operable optionally for draining water from the tub at a rate greater than that at which water is supplied by the jets to permit substantially complete emptying of the tub of water while supply by the jets is continued.

13. In combination in a washer, a tub having side walls and a bottom, a basket for receiving articles to be washed, means mounting the basket in the tub for rotation about an upright axis, 35 means for supplying water to the tub in the form of a plurality of separate, relatively fine high velocity jets directed downwardly into the basket, an overflow drain opening through one of the side walls of the tub at a height permitting filling of the tub with water to a predetermined level below the top of the sidewalls and to a depth sufficient substantially to immerse completely the basket and articles contained therein, said drain providing a discharge exit path 40 on the outside of the tub for excess water introduced into the tub while the water is at said

level, and means operable optionally for draining water from the tub at a rate greater than that at which water is supplied by the jets to permit substantially complete emptying of the tub of water while supply by the jets is continued.

14. In combination in a washer, a tub having side walls and a bottom, a basket for receiving articles to be washed, means mounting the basket in the tub for rotation about an upright axis, means for supplying water to the tub in the form of a plurality of separate, relatively fine high velocity jets directed downwardly into the basket, an overflow drain opening through one of the side walls of the tub at a height permitting filling of the tub with water to a predetermined level below the top of the side walls and to a depth sufficient substantially to immerse completely the basket and articles contained therein, said drain providing a discharge exit path on the outside of the tub for excess water introduced into the tub while the water is at said level, another drain opening into the tub below the overflow drain substantially at the level of the tub bottom, and closure means for said other drain permitting optional filling or substantially complete emptying of the tub.
